UNITED STATES PATENT OFFICE.

JOSEPH LEON GOBEILLE AND HERMAN MATZEN, OF CLEVELAND, ASSIGNORS TO W. L. SHARP & SON, OF STEUBENVILLE, OHIO.

DESIGN FOR A FIRE-PLACE BACK.

SPECIFICATION forming part of Design No. 17,343, dated May 10, 1887.

Application filed April 12, 1887. Serial No. 234,553. Term of patent 7 years.

To all whom it may concern:

Be it known that we, JOSEPH LEON GOBEILLE and HERMAN MATZEN, citizens of the United States, residing at Cleveland, in the 5 county of Cuyahoga and State of Ohio, have invented and produced a new and original Design for Backs of Grates and Fire-Places; and we do declare the following to be a full, clear, and exact description of the same, reference being had to the accompanying photograph, forming a part thereof.

The photograph is a view in elevation of our design for backs for grates and fire-places, which is clearly shown therein.

15 The design consists as a whole of three parts, comprising a central back portion and two side panels.

The leading feature of our design for fire-place backs is a rectangular depressed portion 20 or panel scalloped or grooved around its edges, and in that portion having the general appearance of the inside of a shell. Within this panel is a representation in raised outline of flames extending upward, and upon 25 these flames rests the body of a dragon with wings spread, which appears to be enveloped in the rising flames. On the side panels the dragon alone is shown enveloped in flame and surrounded by the shell-like scalloped portion 30 referred to. In the center panel, however, the figure of St. George is shown standing upon the dragon and driving a spear into its body, so that the center panel contains on a depressed surface the raised outlines showing 35 flames enveloping a dragon, and also the figure of St. George, which appears to be standing

over and killing the dragon. The said panels are all exactly alike, except that the figure of St. George is omitted from all except the middle one. The surface of the several portions 40 is cross-barred and formed with some ornamental projection in the inside of each of the squares formed by the cross-bars.

Having described our invention, we claim—

1. In a design for grate and fire-place backs 45 herein shown and described, the side panels, the same consisting of the depressed surface having upon it the raised figure of a dragon enveloped in flame, substantially as shown and described.

2. In a design for grate and fire place backs, the rear panel, the same consisting of the depressed surface having upon it the raised figures of St. George killing a dragon, the said figures being enveloped in rising flames and 55 surrounded by a shell-like scalloped surface, substantially as described and shown.

3. The design for fire-place backs, consisting of the depressed central portions carrying the figure of the dragon enveloped in flame and 60 surrounded by a scalloped shell-like portion, the flat surface of the back being cross-barred, and the oppositely-placed side panels, substantially as shown and described.

In testimony whereof we affix our signatures 65 in presence of two witnesses.

JOS. LEON GOBEILLE.
HERMAN MATZEN.

Witnesses:

F. H. GOFF,
GEORGE H. REINBERGER.
